(57) **CLAIM**

The ornamental design for a digital thermometer as shown and described.

DESCRIPTION

FIG. 1 is a top front perspective view of the invention showing a digital thermometer;

FIG. 2 is a front view thereof;

FIG. 3 is a back view thereof;

FIG. 4 is a right view thereof;

FIG. 5 is a left view thereof;

FIG. 6 is a top view thereof;

FIG. 7 is a bottom view thereof; and,

FIG. 8 is a top back perspective view thereof.

The portions of the digital thermometer shown in broken line form no part of the claimed design.
